United States Patent

Des. 237,527
Patented Nov. 4, 1975

237,527

CULTIVATOR TINE

Ary van der Lely, 10 Weverskade,
Maasland, Netherlands

Filed Oct. 4, 1974, Ser. No. 512,049

Claims priority, application Switzerland Apr. 11, 1974

Term of patent 14 years

Int. Cl. D15—03

U.S. Cl. D40—1 E

FIG. 5

FIG. 6

FIG. 8

FIG. 10

FIG. 7

FIG. 9

FIG. 11

FIG. 12

FIG. 13

FIG. 1 is a side view of a cultivator tine embodying my new design and mounted on a support shown in broken lines for illustrative purposes only;

FIG. 2 is a side elevation, viewed in the direction of arrow II in FIG. 1,

FIG. 3 is a side elevation, viewed in the direction of arrow III in FIG. 2,

FIG. 4 is an elevation, viewed in the direction of arrow IV in FIG. 2,

FIG. 5 is a perspective view of the cultivator tine embodying my new design,

FIGS. 6 to 13 are cross-sections along the respective lines in FIG. 5.

I claim:

The ornamental design for a cultivator tine, substantially as shown and described.
